UNITED STATES PATENT OFFICE.

EDWARD MOORE, OF SYRACUSE, NEW YORK.

MOTOR-TRACTOR.

1,150,290.

Specification of Letters Patent. Patented Aug. 17, 1915.

Application filed August 10, 1914. Serial No. 856,031.

To all whom it may concern:

Be it known that I, EDWARD MOORE, a citizen of the United States, and resident of Syracuse, in the county of Onondaga, in the State of New York, have invented new and useful Improvements in Motor-Tractors, of which the following, taken in connection with the accompanying drawings, is a full, clear, and exact description.

10 This invention relates to certain improvements in motor tractors adapted to be used more particularly for farm work for operating plows, drags, harrows and other tilling implements requiring repeated traversing of 15 a field, or it may be temporarily installed in any convenient locality for operating other machinery, such as threshing, wood-sawing, silo-filling and fodder-cutting machines, as well as any other devices which might be operated by motor power.

20 The main object, therefore, is to provide a commercially practicable and economical motor truck or tractor which may be propelled under its own power and used for 25 all the purposes mentioned, without in any way altering its structure.

Another object is to render the operation and control of the machine so easy and simple that anyone skilled in the handling of 30 ordinary farm utensils may successfully operate the same.

35 A further object is to localize all of the controls within easy reaching distance of the operator at a particular part of the truck so that the machine may be steered, propelled forward or backward at any speed, or stopped, without necessitating change of position of the operator.

40 A still further object is to distribute the driving members for the traction wheel in such manner as to equalize the driving strain thereon, so that it may run with a minimum amount of friction and thereby increase the durability of this important part of the machine.

45 Another important object is to drive the traction wheel through the medium of a single concentric row of gear teeth, having internal and external working faces, on the 50 same pitched circle and in spaced relation so as to permit the driving pinions co-operating with said working faces to expel any dirt, stones or other foreign matter which may tend to lodge or accumulate between 55 the gear teeth.

Other objects and uses relating to specific parts of the machine will be brought out in the following description.

In the drawings, Figures 1 and 2 are respectively a top plan and a side elevation 60 of a motor tractor embodying the various features of my invention. Fig. 3 is a horizontal sectional view of the same machine taken on line 3—3, Fig. 2, except that it omits the front end and left-hand side of 65 the machine carrying the steering and land wheels. Fig. 4 is a longitudinal vertical section through a portion of the left-hand side of the machine showing more particularly the mechanism for shifting the sliding 70 disks, and taken on line 4—4, Fig. 3. Fig. 5 is an enlarged detail section taken on line 5—5, Fig. 3, showing the universal bearing for one of the counter-shafts. Fig. 6 is an enlarged detail sectional view taken on line 75 6—6, Fig. 3, showing the hinged bearing for one of the counter-shafts. Fig. 7 is a vertical sectional view through the front end of the machine, taken on line 7—7, Fig. 1, showing the steering gear. Fig. 8 is a vertical sectional view through the left-hand side of the frame near the land wheel, showing the manner of adjusting said wheel vertically, and taken on line 8—8, Fig. 1. Fig. 9 is a vertical sectional view through a portion of the rear end of the machine, taken on 80 line 9—9, Fig. 1. Fig. 10 is a detail sectional view through the center portion of the machine, taken on line 10—10—, Fig. 1, showing more particularly the equalizing 85 lever for shifting the friction disks along their respective counter-shafts. Fig. 11 is an enlarged transverse vertical sectional view taken on line 11—11, Fig. 3, showing the hand lever and foot lever for controlling 90 the shifting movements of the sliding disks and their counter-shafts.

As illustrated, this tractor is essentially a three-wheel truck having a single traction wheel —1—, a steering wheel —2— and a 100 land wheel —3—, all revolubly mounted upon a main frame or platform —4— and adjusted to support said frame in a substantially horizontal position, the tractor —1— being of relatively large diameter and face 105 width as compared with the corresponding dimensions of the wheels —2— and —3— so as to constitute the main support for the frame —4— and mechanisms carried thereby, and at the same time to afford ample 110

traction surface for propelling the machine, and other implements attached thereto, along or upon the surface of the ground.

The main frame —4— is elongated in the direction of the line of draft and comprises outer and inner lengthwise parallel bars —5— and —6— of substantially the same length and constituting one side of the frame, said bars being held in fixed spaced relation by relatively short end and intermediate cross bars —7—, —8— and —9— which are secured to the lengthwise bars —5— and —6— by junction plates —10—, the rear cross bar —8— and intermediate bar —9— being spaced apart a sufficient distance to receive the traction wheel —1— between them, while the front bar —7— and intermediate bar —9— are spaced a relatively shorter distance apart to permit the free operation of the steering wheel —2— in the intervening space.

The rear bar —8— is provided with an extension —8'— toward the opposite side of the machine, the outer end of said extension being rigidly united by a junction-plate —11— to a forwardly diverging brace bar —12— having its forward end rigidly united by a junction-plate —13— to the rear end of a somewhat longer brace bar —14— which is rigidly secured at its front end to the junction-plate —10— connecting the adjacent ends of the lengthwise bar —6— and front bar —7—.

The intermediate portion of the bar —14— is braced to the lengthwise bar —6— by means of an additional cross bar —9'— forming an extension of the bar —9— and having its inner end rigidly united to the plate —10— and its outer end similarly united to the bar —14— by means of a junction-plate —15—.

As a further means of stiffening the frame and supporting the engine-bed, presently described, the junctions of the extension —8'— and bar —12— at the rear of the machine are connected by a lengthwise bar —16— to the bar —14— just at the rear of the cross bar —9'—, said bar —16— being spaced some distance from and parallel with the bar —6— and has its rear end rigidly secured to the junction-plate —11— and its forward end secured by a similar junction-plate —11'— to the bar —14—, all of said frame bars being preferably made of channel iron for lightness and strength.

The frame bars —12— and —14— are disposed diagonally to the line of draft, so as to converge in approximately the vertical plane of the produced axis of the traction wheel —1—, in which plane the axis of the land wheel —3— is located, said diagonal bars —12— and —14—, together with the extension cross bars —8'— and —9'— and lengthwise bar —16—, constituting what may be termed an out-rigging for support-

ing the land wheel —3— and other adjuncts of the machine hereinafter described.

The traction wheel —1— is journaled upon a relatively short stationary cross shaft —17— having its ends secured in suitable boxes —18— on the lengthwise frame bars —5— and —6— by means of set screws —19—, thereby supporting the traction wheel in the open space between the lengthwise bars —5— and —6—, and also between the cross bars —8— and —9—. This traction wheel comprises a hub —20— having flanged ends connected by circular plates or webs —21— and —22— to a circular flanged rim —23— having a traction tire —24— riveted or otherwise secured thereto, the inner and outer marginal edges of the circular plates or webs —21— and —22— being also riveted or otherwise secured to the flanges of the hub —20— and rim —23—, thereby forming a light, yet strong and durable, traction wheel capable of excluding the dust from the interior thereof.

The inner disk —22— is provided with a concentric row of axially projecting gear pins or teeth —25— of circular cross section so as to form internal and external working faces having a common pitch circle, and adapted to mesh, respectively with an internal pinion —26— and an external pinion —26'—. These pinions are secured to the inner ends of separate counter-shafts —27— and —27'— which are journaled in bearings —28— and —29— parallel with and at opposite sides of the axis of the traction wheel, as shown more clearly in Fig. 3, for receiving and supporting separate friction disks —30—. These friction disks are feathered or splined upon their respective counter-shafts —27— and —27'— to rotate therewith and to move axially thereof, and for this purpose the counter-shafts are angular or square in cross section and are passed through corresponding openings in the centers of the disks —30—.

Rotary motion is imparted to the disks —30— by means of coöperative driving disks —31— which are secured to the opposite ends of a motor shaft —32—, the latter being journaled on a bed-plate —33— bridging the space between the lengthwise bars —6— and —16— and bolted or otherwise secured thereto. The motor shaft —32— is disposed at right angles to and in approximately the same plane as the axis of the traction wheel, so that the disks —31— are disposed at opposite sides of said axis for frictional contact with the inner faces of the friction wheels —30—.

The outer end faces of the disks —31—, with which the sliding disks —30— engage, are parallel with each other and therefore parallel with the axis of the traction wheel, the disks —30— being adapted to frictionally engage their corresponding

isks —31— at the same side of and the same distance from the axis of the driving disks, so as to revolve the driven disks and their corresponding shafts —27— and 5 —27'— and pinions —26— and —26'— in reverse directions, thereby imparting rotary motion to the traction wheel in one direction or the other, according to the position of the driven disks —30— at one side or the 10 other of the axis of the motor shaft, it being understood that the disks —30— may be moved to either side of said axis for reversing the direction or changing the speed of movement of the machine, or they may be 15 stopped at the center, when the machine will be at rest.

Suitable means is provided for moving the sliding disks —30— axially and simultaneously the same distance in the same direction, and for this purpose the hubs of the disks —30— are provided with annular grooves for receiving non-rotatable collars —34— having pins projecting into the grooves, said collars being pivotally connected to crank arms —35— which in turn are secured to vertical rock shafts —36— and —36'— on the rear bar —8— and intermediate cross bar —9—. These rock shafts are provided with crank arms —37— and —37'— extending in the same direction toward the traction wheel from their respective shafts —36— and —36'— and have their free ends connected by links —38— and —38'— to the opposite ends of an equalizing lever —39— which is fulcrumed or pivoted intermediate its ends at —40— to the under side of the bed-plate —33—, as shown more clearly in Fig. 10, the rock shaft —36'— being also provided with an oppositely projecting crank arm —41— having its free end connected by a link —42— to the lower end of a hand lever —43— which is fulcrumed at —44— to the lengthwise frame bar —16—, as shown in 45 Figs. 4 and 11.

It is now clear that by rocking the lever —43— forward and backward simultaneous axial movement will be transmitted to the disks —30— to move the same across the 50 face of the disks —31— toward and from the center and to either side thereof for varying the speed and reversing the direction of movement of the traction wheel, through the medium of the counter-shafts —27— and —27'— and pinions —26— and —26'—. For example, assuming that the friction disks —30— are in the position shown in Fig. 3, at one side of the axis of the motor shaft for driving the machine in 55 one direction, and that it is desired to reverse the machine, then it is simply necessary to rock the upper end of the lever —43— forwardly a sufficient distance to slide the disks —30— to the opposite side 60 of the motor shaft, under which conditions

the link —42— will be moved in the direction indicated by arrow X, while the link —38— will be moved in the opposite direction indicated by arrow Y, thereby operating the lever —39— to shift the link —38— in the direction indicated by arrow Z, the several crank arms, lever and links being so relatively arranged and proportioned as to transmit the same amount of movement to the disks —30— in the same direction by a predetermined degree of movement of the operating lever —43—.

One of the objects in applying the driving pinions —26— and —26'— internally and externally to the corresponding working faces of the gear pinions —25— at diametrically opposite sides of the axis of the traction wheel, is to substantially balance the driving strains and to relieve the traction wheel from binding upon its shaft —17—, thus producing a maximum propelling power without loss or excessive wear.

Another object is to render the intermeshing gears self-cleansing from dirt, stones and other foreign matter which may tend to lodge between the gear pins, since it is evident that any matter which may wedge between the teeth from one side will be forced out by the teeth of the pinion acting from the opposite side.

In order to increase the utility of this machine for other purposes than propelling such machine and implements which may be attached thereto, as for example in driving a wood-sawing machine, fodder-cutter, threshing machine, stump-puller and other apparatus, provision is made for shifting the counter-shafts —27— and —27'— transversely of their axes so as to disengage their respective disks —30— from the driving disks —31— of the engine or motor shaft —32—, which permits the use of the motor shaft for driving a general utility shaft —46— which is journaled in suitable bearings —47— directly over and upon the lengthwise bar —16— of the main supporting frame, said utility shaft being provided with a sprocket wheel connected by a chain —48— to a similar sprocket wheel —48'— on the motor shaft —32—, as shown more clearly in Figs. 1, 2 and 3.

The bearings —28— for the inner ends of the counter-shafts —27— and —27'— are mounted on horizontally swinging arms —49— which are pivoted at —50— to brackets —51— on the inner main frame bar —6—, as shown more clearly in Fig. 3, the pivots —50— being in radial alinement with and close to their corresponding pinions —26— and —26'— so as to prevent disengagement of the pinions with the gear teeth —25— when the outer ends of the counter-shafts are rocked away from each other in disengaging their disks —30— from their driving disks —31—.

The bearings —29— for the outer ends of the counter-shafts —27— and —27'— are mounted upon the upper ends of upright rock arms —53— which are journaled in suitable bearings —54— on the lower side of the frame bar —16—, and are provided with crank arms —55— extending from their bearings —54— toward each other, the adjacent ends of said arms —55— being pivotally connected to links —56— which in turn are pivoted to the opposite ends of a lever —57—. This lever is fulcrumed intermediate its ends at —58— upon the lower end of a vertically movable rod or plunger —59— which is slidable in a bearing —60— on the frame bar —16—, and is adapted to be forced upwardly by a pedal lever —61— against the action of a retracting spring —62—, the latter being interposed between the lower end of the bolt —59— and adjustable bushing —63— in the bearing —60—. The pedal lever —61— is made in the form of a bell-crank fulcrumed at —61— to a bracket on the under side of the frame bar —16— and having its shorter arm engaged with the lower face of the lever —57— and its longer arm extended upwardly above the frame bar —16—, and provided with a foot piece —64—. The spring —62— normally forces the disks —30— into engagement with the driving disks —31— through the medium of the arms —55— and —53—, but by pressing forwardly upon the upper end of the foot lever —61— the shorter arm thereof, operating upon the lever —57— rocks the arms —55— upwardly, thereby rocking the arms —53— and adjacent ends of the counter-shafts —27— and —27'— carried thereby away from each other to disengage the corresponding disks —30— from said driving disks, the bearings —29— being swiveled in the upper ends of the arms —53— to allow the lateral rocking movement of the counter-shafts —27— and —27'— about the pivots —50— of the supporting arms —49— for the inner ends of the rock shafts, in the manner previously described. The object of these special mountings for the counter-shafts is to permit them to be moved laterally to disconnect their disks —30— from the driving disks —31— without cramping said shafts or disconnecting their pinions from the gear teeth —25—. The steering wheel —2— is journaled in a suitable fork —70— having its upper end provided with a spindle —71— which is journaled in a plate —72— connecting the front ends of the bars —5— and —6— and secured thereto by suitable bolts, as shown more clearly in Figs. 1 and 7, the portion of the fork —70— at the junction with the spindle —71— being provided with a relatively broad flat bearing in turning engagement with the underside of the plate —72—.

A worm gear —73— is secured to the upper end of the steering post or spindle —71— and is engaged by a worm —74— on the adjacent end of a flexible shaft —75—, the latter being journaled in bearings —76— on the frame bar —14— and is provided with a hand wheel —77— by which it may be turned to transmit turning motion to the steering wheel.

In order that the steering wheel may be operated positively in either direction, the flexible shaft —75— is preferably composed of end and intermediate sections, as shown more clearly in Fig. 1, the intermediate section being journaled in the bearings —76— and its opposite ends connected by universal joints —78— to the end sections.

The land wheel —3— is adjustable vertically and for this purpose is mounted on an axle stub —79—, preferably square in cross section and slidable vertically in a U-shape yoke —80— which is secured to the under side of the bar —14—, said axle stub being provided with a transverse bolt opening adapted to register with any one of a series of similar openings —92— in opposite sides of the yoke for receiving a locking pin —93— by which the axle stub and land wheel thereon may be held in any of its adjusted positions.

Any suitable motor, such as an internal combustion engine, may be mounted upon the bed-plate —33— and connected to the crank shaft —32— in the usual manner.

The auxiliary shaft —46— may be provided at its rear end with a clutch section —95— for engagement by a starting crank —96— to start the engine, although it is evident that any of the well known forms of self-starting devices may be employed if desired, and that the clutch may be used for connection with any other shaft or machine which it is desired to drive, either simultaneously with the operation of the traction wheel in propelling the machine along the ground or independently of the propulsion of said machine.

A suitable seat for the driver, not shown, may be mounted upon the main supporting frame within convenient reaching distance of the steering wheel —77— and levers —43— and —61— by which the operation of the machine is controlled.

It is also evident that a plow harrow, 120 cultivator or any other implement which it is desired to operate by means of the tractor may be attached thereto by any suitable means, not necessary to herein illustrate or describe for the reason that the attaching means will depend somewhat upon the implement propelled by the tractor.

In operation, the speed and direction of movement of the machine is controlled entirely by the lever —43—, while the driving connection between the friction disks is con- 130

trolled by the pedal lever —61—, the auxiliary shaft —46— being driven at all times when the motor is in operation.

What I claim is:

5. 1. A motor tractor comprising a motor-driven shaft having opposed friction disks, additional friction disks in radially sliding contact with their respective first-named disks, separate counter-shafts driven by the 70 additional disks, means for shifting said additional disks, a traction wheel having a single circular row of gear pins concentric with its axis, and pinions on the counter-shafts operating respectively upon the gear pins from opposite sides thereof. 75
10. 2. In a motor tractor, the combination of a traction wheel having a concentric series of axially projecting gear teeth, separate pinions engaging said teeth internally and externally respectively, a motor-driven shaft, and mechanisms actuated by the motor shaft for driving the pinions simultaneously in opposite directions. 80
15. 3. In a motor tractor, a truck having a single propelling wheel provided with a single concentric row of teeth, separate pinions meshing respectively internally and externally with the teeth, and motor-driven mechanisms on the truck for driving said pinions simultaneously in opposite directions including devices for changing the direction of rotation of the pinions. 85
20. 4. In a motor tractor, a truck having a single propelling wheel provided with a single concentric row of teeth, separate pinions meshing respectively internally and externally with the teeth, and motor-driven mechanisms on the truck for driving said pinions simultaneously in opposite directions including devices for varying the speed of rotation of the pinions. 90
25. 5. In a motor tractor, a truck and propelling means therefor comprising a motor shaft having opposed friction disks, counter-shafts at opposite ends of and at right angles to the motor shaft, additional friction disks splined on their respective counter-shafts and contacting with the first-named disks in such manner as to be driven simultaneously in reverse directions, means for shifting the additional disks along their respective shafts to vary the speed and direction of movement of the counter-shafts, a traction wheel having a gear provided with internal and external working faces, and pinions on the counter-shafts operating respectively on said internal and external working faces of the gear. 95
30. 6. In a motor tractor, a truck and propelling means therefor comprising a motor shaft having opposed friction disks, counter-shafts at opposite ends of and at right angles to the motor shaft, additional friction disks splined on their respective counter-shafts and contacting with the first-named disks in such manner as to be driven simultaneously in reverse directions, means for shifting the additional disks along their respective shafts to vary the speed and direction of movement of the counter-shafts, a traction wheel having a gear provided with internal and external working faces, and pinions on the counter-shafts operating respectively on said internal and external working faces of the gear. 100
35. 7. In a motor tractor, a truck, a motor shaft and a traction wheel both mounted on the truck, a concentric row of gear teeth on the traction wheel having internal and external working faces on the same pitch circle, separate pinions meshing respectively with the internal and external working faces, and means for transmitting motion from the motor shaft to said pinions for driving the traction wheel in one direction. 105
40. 8. In a motor tractor, a truck, a motor shaft and a traction wheel both mounted on the truck, a concentric row of gear teeth on the traction wheel having internal and external working faces on the same pitch circle, separate pinions meshing respectively with the internal and external working faces, and means for transmitting motion from the motor shaft to said pinions for driving the traction wheel in one direction, and additional means for changing the relation between parts of said transmitting means in such manner as to vary the speed of rotation of the pinions. 110
45. 9. In a motor tractor, a truck, a motor shaft and a traction wheel both mounted on the truck, a concentric row of gear teeth on the traction wheel having internal and external working faces on the same pitch circle, separate pinions meshing respectively with the internal and external working faces, and means for transmitting motion from the motor shaft to said pinions for driving the traction wheel in one direction, and additional means for changing the relation between parts of said transmitting means to change the direction of rotation of said pinions and traction wheel driven thereby. 115
50. 10. In a motor tractor, a truck having a single traction wheel for propelling the same, a motor shaft mounted on the truck at right angles to and in approximately the same plane as the axis of the traction wheel, counter-shafts also mounted on the truck at opposite sides of the axis of the traction wheel and in substantially the same plane 120
55. 65. 11. In a motor tractor, a truck having a single traction wheel for propelling the same, a motor shaft mounted on the truck at right angles to and in approximately the same plane as the axis of the traction wheel, counter-shafts also mounted on the truck at opposite sides of the axis of the traction wheel and in substantially the same plane 125
60. 65. 12. In a motor tractor, a truck having a single traction wheel for propelling the same, a motor shaft mounted on the truck at right angles to and in approximately the same plane as the axis of the traction wheel, counter-shafts also mounted on the truck at opposite sides of the axis of the traction wheel and in substantially the same plane 130

as that of the motor shaft, coöperative sets of friction disks mounted respectively on the motor shaft and counter-shafts for rotating said counter-shafts simultaneously in opposite directions, means for shifting the disks on the counter-shafts relatively to those on the motor shaft for varying the speed of rotation of said counter-shafts, and

additional means actuated by the counter-shafts for driving the traction wheel.

In witness whereof I have hereunto set my hand this 31st day of July 1914.

EDWARD MOORE.
